(57) **CLAIM**

I claim the ornamental design for a safety transition ladder, as shown and described.

DESCRIPTION

FIG. 1 is a perspective view of a safety transition ladder according to the present disclosure.

FIG. 2 is a right-side view of the safety transition ladder according to the present disclosure.

FIG. 3 is a left-side view of the safety transition ladder according to the present disclosure.

FIG. 4 is a rear-side view of the safety transition ladder according to the present disclosure.

FIG. 5 is a front-side view of the safety transition ladder according to the present disclosure.

FIG. 6 is a top plan view of the safety transition ladder according to the present disclosure; and,

FIG. 7 is a bottom plan view of the safety transition ladder according to the present disclosure.

The broken lines in the drawings depict environmental portions that form no part of the claimed design.
